MOUNTING OF THE DOORS OR COVERS OF
PRESSURE VESSELSHenry Maurice Hattersley Pickard, Leeds,
EnglandApplication February 7, 1941, Serial No. 377,931
In Great Britain November 13, 1939

5 Claims. (Cl. 16—129)

This invention relates to the doors or covers of pressure vessels such as vulcanisers, cures, kiers, autoclaves, retorts and the like and concerns hinge mountings for said doors or covers which comprise one or a pair of outwardly projecting brackets carried by the body of the vessel, a single hinge pin or a pair of axially aligned hinge pins supported by the bracket or brackets and a pair of arms connected to the hinge pin or respective hinge pins.

An object of the invention is to provide simple means for enabling a door or cover mounted in the manner aforesaid to be readily adjusted by movement in a plane parallel to the mouth of the vessel, in a direction approximately perpendicular to the hinge axis.

A further object of the invention is to effect the aforesaid adjustment by pivotally mounting the door on one of the hinge arms so that the door can tilt on the pivot under the control of a screw device to change its position laterally with respect to the vessel mouth. Another object is to provide a mounting having the aforesaid characteristics and which is reversible to enable the door to be mounted for either right-hand or left-hand opening and with the pivot below the level of the adjusting device in each case.

A still further object of the invention is to provide for adjusting the positions of the hinge arms along the hinge axis in addition to providing the aforesaid tilting movement, thereby affording adjustment in a direction parallel to that of the hinge axis. This will permit repositioning of the door to compensate for slight displacement thereof in a direction parallel to the hinge axis resulting from tilting movement about the pivot, as well as enabling intentional adjustment to be made in the said direction.

Another object of the invention is to provide a hinge mounting for a vessel door which in addition to affording the adjustment aforesaid, readily enables the door when set in a particular position to be bodily moved towards or away from the vessel mouth, thereby permitting such adjustment of the door as will ensure uniform seating pressure at all points around the door.

In order that the invention may be readily understood, reference is directed to the accompanying drawing illustrating a door mounting of a practical form in accordance therewith and wherein

Figure 1 is a front elevation of the door and its mounting,

Figure 2 is a fragmentary plan view of the door

and its mounting, showing also the adjacent part of the vessel, and

Figure 3 is a side elevation.

In the construction illustrated a plate-like supporting bracket 1 has a pair of side extensions 1a, by means of which the bracket 1 can be attached to the mouthpiece or endpiece 2 of the pressure vessel 3. The extensions 1a extend behind and are bolted to the projecting flange 2a of the mouthpiece 2. The bracket 1 supports a single vertical hinge pin 14 which extends through upper and lower bearing sockets 15a, 15b, which are each connected to the bracket 1 by means of screw studs 15c held by nuts 15d, with ability for adjustment forwardly or rearwardly, as required. The hinge pin 14 is also capable of adjustment vertically by freely supporting its lower end on an adjusting screw 16 screwed into the lower socket 15b. To the hinge pin 14 are clamped the lower and upper hinge arms 17a, 17b which are of trough or channel shape, so as to accommodate within them four bosses 18a, 18a, 18b, 18c, on the cover 6, the two latter (18b, 18c) being provided with flat faces 18d. In the floors of the trough or channel like arms 17a, 17b, opposite the bosses 18a, 18b, 18c, are openings which are slightly larger in diameter than the shanks of the studs 19a, 19b and 19c which pass through said openings and screw into the bosses 18a, 18b, 18c. The stud 19b however is provided with a neck or collar which fits its opening in the arm 17a, so as to act as a pivot or fulcrum about which the door 6 can swing, said pivot or fulcrum being so arranged with respect to the centre of gravity of the door that there is a tendency for the door 6 to swing upon this pivot stud 19b in the direction indicated by arrow B. This swinging movement is limited by a screw stud 20 which engages a tapped hole 21b in the end wall of the arm 17b and bears against the face 18d of the boss 18c. The "seating" of the door 6 may thus be adjusted laterally, the door 6 being clamped to the arms 17a, 17b, by screwing down the studs 19a, 19b and 19c. In the drawing, the door 6 is shown as mounted for left-hand opening. If the door is to be mounted for right-hand opening, the same components will suffice without the necessity of any metal cutting or other arduous operation being performed. The bracket 1 is first reversed and bolted on the opposite side of the mouthpiece 2 and the door 6 swung round through 180° until the boss 18b reaches position C and boss 18c reaches position D. The two arms 17a, 17b are then transferred to positions diametrically or

diagonally opposite to those shown in Figure 1, so that arm 17a is above arm 17b. The pivot bolt 19b is now used to engage the boss 18c (which is at position D) and the door-swing limiting or adjusting screw 20 engages with the tapped hole 21a of arm 17a.

The invention is applicable to the doors or covers of cylindrical vessels, in general, provided that the locking means for the door or cover is such as to be unaffected by the turning movement of the door or cover, and is especially applicable to a door secured by latches provided on the body of the vessel and engaging over the rim of the door.

The hinge mounting above described is of such a form as to be capable of fitting for either right or left hand opening about a vertical axis or indeed for opening about an axis other than vertical, without the necessity of any metal cutting or other operations being effected during the process of erecting the door or cover.

This enables a horizontal or inclined cylindrical pressure vessel which is subject to excessive localised corrosion, for example, along the bottom to be turned about the longitudinal axis to bring a fresh part of the barrel to the bottom, the door or cover being refitted in the same position it formerly occupied.

I claim:

1. A hinge mounting for the door of a cylindrical pressure vessel comprising a bracket adapted for attachment to the vessel to outwardly project therefrom, a hinge pin supported by said bracket, a pair of arms attached to said hinge pin, bosses on the door in the regions of the respective arms, a pair of studs adapted to be screwed into said bosses and adapted to selectively serve as a pivot for the tilting of the door, openings formed in said arms for the passage of the respective studs and which are of greater diameter than the shanks of said studs, a neck provided on one of the studs which enters the associated arm opening as a close fit therein to provide a fulcrum about which the door can tilt, and a threaded hole in an end of each arm for the engagement into the arm, other than the one which for the time being engages the fulcrum stud, of a screw which constitutes an adjustable stop for contacting with the adjacent door boss to limit the tilting movement of the door, the said arrangement permitting the same pair of arms to be employed for left-hand or right-hand opening of the door, the pivot in either case being associated with the lowermost arm.

2. A hinge mounting for the door of a cylindrical pressure vessel comprising a bracket adapted for attachment to the vessel to outwardly project therefrom, a pair of tubular sockets, a screw-threaded stem radially extending from each of said sockets and passing through holes formed in the bracket, screw nuts fitted on said stems for adjustably clamping same to the bracket, an adjustable hinge-pin-supporting screw fitted in the bore of one of said sockets, a hinge pin rotatably mounted in said sockets and supported at one end by the said adjustable supporting screw, a pair of arms attached to said hinge pin in parallel and spaced relation, two openings formed in each of said arms, two pairs of bosses on the door, two pairs of screw studs adapted to be passed through the arm openings and to screw into the door bosses, said studs being of less diameter than the arm openings, a neck on one of said studs which is adapted to

enter an opening in either of the arms as a close fit in said opening, said neck-fitted stud constituting a fulcrum for tilting movement of the door, a threaded hole formed in an end portion of each arm, and an adjusting screw adapted to be fitted into a selected one of said threaded holes, said screw being arranged to constitute an abutment for a door boss other than the one at the fulcrum point, for the purpose of controlling the extent to which the door can tilt about said fulcrum point.

3. In a hinge mounting for the door of a cylindrical pressure vessel, a bracket carried by said vessel and comprising pin supporting means, a hinge pin carried by said supporting means, a pair of spaced arms fixedly carried by said pin and extending over said door, each of said arms being provided near its free end with an opening, and a pair of studs carried by said door in register with said openings respectively and being of smaller diameter than the diameter of said openings and being received within said openings, one of said studs being provided with a collar of substantially the same diameter as its said opening and which fits snugly but rotatably therein constituting a pivot, whereby said door may swing about said collared stud as a pivot within the play of the non-collared stud in its opening.

30 4. In a hinge mounting for the door of a cylindrical pressure vessel, a bracket carried by said vessel and comprising pin supporting means, a hinge pin carried by said supporting means, a pair of spaced arms fixedly carried by said pin and extending over said door, each of said arms being provided near its free end with an opening, and a pair of studs carried by said door in register with said openings respectively and being of smaller diameter than the diameter of said 35 openings and being received within said openings, one of said studs being provided with a collar of substantially the same diameter as its said opening and which fits snugly but rotatably therein constituting a pivot, the arm carrying the non-collared stud being terminally provided with adjustable screw means, and the door being provided adjacent the non-collared stud with abutment means engageable with said adjustable screw means, whereby the degree of movement 40 of said door about said collared stud may be controlled.

5. In a hinge mounting for the door of a cylindrical pressure vessel, a bracket carried by said vessel and comprising pin supporting means, a hinge pin carried by said supporting means, a pair of spaced arms fixedly carried by said pin and extending over said door, each of said arms being provided near its free end with an opening, said door being provided with a pair of tapped bosses in register with said openings respectively, a pair of threaded studs screwed into said bosses and being of smaller diameter than the diameter of said openings and being received within said openings, one of said studs being provided with a collar of substantially the same diameter as its said opening and which fits snugly but rotatably therein constituting a pivot, the said boss receiving the non-collared stud being provided with a flat face on its side toward the free end of its arm, and an adjusting screw carried by the free end of the said arm and adapted to engage said flat face of said boss for limiting the play of said non-collared stud in its said opening.

HENRY MAURICE HATTERSLEY PICKARD.
